UNITED STATES PATENT OFFICE.

HERBERT B. CHURCH, OF BLOOMFIELD, NEW JERSEY, ASSIGNOR TO CONSOLIDATED SAFETY PIN COMPANY, OF BLOOMFIELD, NEW JERSEY, A CORPORATION OF NEW JERSEY.

MACHINE FOR CARDING SAFETY-PINS, &c.

1,133,363.

Specification of Letters Patent. Patented Mar. 30, 1915.

Application filed August 13, 1908. Serial No. 448,301.

To all whom it may concern:

Be it known that I, HERBERT B. CHURCH, a citizen of the United States, residing in Bloomfield, in the State of New Jersey, have 5 invented certain new and useful Improvements in Machines for Carding Safety-Pins, &c., of which the following is a specification, reference being had to the accompanying drawings, forming a part hereof.

10 This invention has for its object the production of a machine which shall be capable of applying safety pins or similar pins to the cards upon which they are usually sold with great rapidity, with certainty, and in a 15 thoroughly satisfactory manner, and it consists in certain mechanisms and mechanical devices for performing the various functions necessary to the accomplishment of the general result desired.

20 In the machine in which the several inventions or improvements are embodied, as illustrated herein, the pins are successively placed in a carrier, such of them as may be closed are opened, the point members are 25 brought to a common position, the point members, in a group comprising the desired number, usually twelve, are made to enter the card which is presented for the purpose, the pins are closed, and the entire group, 30 with the card upon which they are mounted, is withdrawn from the carrier. All of these operations are performed automatically and with great rapidity.

35 The several mechanisms which are involved in the several operations just referred to will be more particularly described hereinafter with reference to the accompanying drawings in which they are illustrated as embodied in a single machine.

40 In such drawings Figure 1 is a top view of the machine. Fig. 2 is an outline view of the machine as seen in elevation from the right hand in Fig. 1. Fig. 3 is a rear end elevation of the machine. Fig. 4 is a front 45 end elevation of the machine with the conveyer and associated parts removed. Fig. 5 is a view in section on the irregular plane indicated by the line 5—5 of Fig. 1 looking toward the left in said figure. Figs. 6 and 50 7 are detail views in side elevation illustrating in different positions the means for transferring the pins from the pin guide to the chain, a portion of the guide, the chain and the devices for opening such pins

as are closed being also shown. Fig. 8 is 55 a top view of the end of the guide. Fig. 9 is an end view of the guide. Fig. 10 is a detail view in front elevation of the means for transferring pins from the guide to the chain, and the device for turning such pins 60 as are improperly presented. Figs. 11, 12 and 13 are detail views illustrating the operation of the devices for holding the card or sticking the pins in the card, for closing the pins and for withdrawing the pins and 65 card from the chain. Fig. 14 is a detail view of the pin closer. Fig. 15 is a detail view illustrating the operation of the devices for withdrawing the pins and card from the chain. Figs. 16, 17 and 18 are detail views of one of the pairs of cams employed in the operation of certain of the parts of the machine as explained herein- 70 after.

75 In the following description the devices which are directly involved in the several operations performed upon the pins will be explained in detail without reference to the gearing by which the devices are operated from the driving shaft of the machine, and 80 thereafter the arrangement of the gearing will be explained as far as may be necessary.

The pins to be carded are dumped into a hopper *a* (Fig. 5) just as they come from the pin making or finishing machine, some 85 being closed, that is, with pin points engaging the heads or shields, and others being open. In the bottom of the hopper is a feeder *a'*, consisting of a roll or disks mounted upon a shaft *a²* and having projecting points *a³*. The feeder picks out the pins separately from the mass in the hopper and discharges them into the box *b'* of a bucket conveyer *b* (Figs. 2, 3 and 5) by 90 which they are discharged through a chute *b²* into a hopper *c* (Figs. 1, 2, 3 and 5). The latter has inclined sides with a slot in the bottom, through which a blade *c²* (Figs. 3 and 5) is raised at intervals for the purpose of clearing the hopper and preventing 95 the entanglement of pins therein. The hopper itself is inclined and the pins are jogged to assist their movement by a plate *c³* which rests upon a cam wheel *c⁴* on a shaft *c⁵*, the plate being pressed down by a spring 100 *c⁶* (Fig. 5).

105 The jogging of the pins causes the coil ends of the pins to drop through the slot

in the bottom, into a guide d formed by plates d' , the pins being suspended therein by the heads or shields which, being slightly thicker than the coils, rest upon the bars 5 which are placed apart only so far as is necessary to permit the coil ends of the pins to pass between them. The guide d is also inclined and the pins are joggled to facilitate their continued movement by a plate 10 d^2 which enters slightly between the bars d' of the guide and rests upon a cam wheel d^3 on a shaft g^3 and being pressed down by a spring d^6 (Fig. 5), while a plate d^5 (Figs. 1 and 5) covers the guide and prevents 15 the pins from being thrust out of the guide. At the lower end of the guide (Figs. 6-9) are springs d^7 which, by contact with the head or shield of the pin, prevent the dropping of the pin from the end of the 20 guide until it is removed therefrom by the devices about to be described, a spring d^8 at the bottom of the guide similarly engaging the coil end of the pin to hold it against accidental movement. 25 The devices which take the pins from the guide and transfer them to the carrier hereinafter mentioned are shown in detail in Figs. 6, 7 and 10 and are indicated in part in Fig. 5. These devices consist, briefly, 30 of nipper jaws or fingers which seize the coil end of the pins between them and then move forward, turning at the same time, so as to insert the point member of the pin in a card prepared therefor in the carrier. It 35 will be observed that each pin is supported in the same position in the end of the guide until it is removed therefrom, so that when the pin is once grasped by the transerrer its head end will be properly presented to 40 the socket in the carrier. The transerrer shown consists of a rod e , capable of a slight endwise movement and also capable of a lateral movement in slots e' formed in stationary members e^2 , and a rod e^3 having a 45 finger e^4 to coöperate with the end of the rod e , and also capable of a slight endwise movement and of a lateral movement in curved slots e^5 formed in the stationary members e^2 . A link e^6 , secured to the rod 50 e^3 , slides on the rod e so as to maintain a certain definite relation between the two rods. The rod e is engaged by the forked end of a lever e^7 pivoted at e^8 , upon a shaft e^9 capable of an oscillating movement in its 55 bearings (Figs. 4 and 5). A lever e^{10} , also pivoted at e^{11} on the shaft e^9 , so as to oscillate therewith and thereon, also supports the rod e and assists in the lateral movement above described, but is engaged directly with the hub of the link e^6 so that it 60 may effect the independent longitudinal movement of the rod e^3 . The shaft e^9 is oscillated through an arm e^{12} connected by a link e^{13} with the strap e^{14} of an eccentric 65 e^{15} on a shaft e^{11} . The levers e^7 and e^{10} , be-

low the shaft e^9 , are provided with rollers, as at e^{17} , which bear upon opposite face cams e^{18} , the lower ends of the levers being connected by a spring e^{19} to hold the rollers in contact with the cams. It will now be 70 understood that when the parts are in the positions represented in Fig. 6, the levers e^7 and e^{10} are held by the spring e^{19} , under control of the cams e^{18} , in such positions as to hold the end of the rod e and the extremity of the finger e^4 away from each other more than the thickness of the coil end of the pin then supported by the springs d^7 and d^8 at the end of the guide. The continued movement of the cams e^{18} 75 then causes the rods e and e^3 to be moved longitudinally so as to firmly grasp the coil end of the pin between the end of the rod e and the extremity of the finger e^4 . At this time, the eccentric e^{15} swings the levers 80 about the axis of the shaft e^9 , causing the rod e to move forward in the straight slot e' . At the same time, through the connection by the link e^6 , the rod e^3 is drawn forward in the curved slots e^5 , causing a partial rotation of the rod e about its own axis and a partial revolution of the rod e^3 about the same axis. This movement turns the pin which is then held by the transerrer from the position shown in Fig. 6 to the 85 position shown in Fig. 7, the head or shield end of the pin being carried into a socket provided therefor in the conveyer or carrier now to be described. 90 The conveyer or carrier consists of a series 95 of sockets f (Figs. 5, 6, 7, 11, 12, 13 and 15) swiveled in the links of a chain f' (see also Figs. 1 and 4) held between guides f^2 and carried by chain wheels f^3 (Fig. 4), suitably mounted in the frame of the machine, 100 one of such chain wheels carrying a ratchet wheel f^4 which is engaged by a pawl f^5 , the latter being actuated by a link f^6 from an eccentric f^7 on a shaft f^8 . A step by step movement is imparted to the chain with a 105 dwell or rest between successive movements, so that each socket f is stopped long enough in line with the transerrer to receive a pin from the transerrer, the succeeding movement of the chain bringing an empty socket 110 into line with the transerrer. 115 As already stated, some of the pins when dumped into the hopper a , are open and others are closed and they are placed in the carrier or conveyer in the same condition. 120 It is necessary, however, that all the pins which are closed shall be opened in order that they may be applied to the card. For this purpose an opener is provided, the position of which is indicated at g in Figs. 1, 4 and 5, the details of construction being sufficiently shown in Figs. 5, 6 and 7. Levers g' , pivoted respectively upon a horizontal axis g^2 , carry at their inner extremities oppositely extending fingers g^3 which are 125 130

adapted to coöperate with the two members of a closed pin as it is held in a socket f of the carrier. The levers are held yielding, as by a spring g^4 , in contact with an intermediate edge cam g^5 on a shaft g^6 . As the shaft rotates it causes the fingers g^3 to approach each other and thereby to press the point member of the pin toward the back member. The cam immediately releases the levers and the point member of the pin is therefore released and is disengaged from the head or shield of the pin. With some styles of pins the formation of the head is such as to cause the pin point to move laterally, when it is pressed and released, sufficiently to clear the opposite side of the head, and therefore to release itself, but with other styles of pins it is necessary to give the pin point a lateral movement by other means and for this purpose the post g^7 , upon which one of the levers g^1 is pivoted horizontally, is itself supported so as to be capable of a slight oscillation about the vertical axis, carrying the lever with it, and to effect such oscillation is provided with an arm g^8 which bears against a face cam g^9 on the same disk or body with the edge cam g^5 so that in the rotation of the cam, one of the fingers g^3 receives, at the proper time, a lateral movement sufficient to carry the pin point clear of the shield. It will be understood that while this opener operates as each socket f of the carrier is brought into line therewith, such operation is not effective unless such socket holds a closed pin. All of the pins which are delivered to the conveyor in a closed position, however, are opened.

It will be seen that the pins may be inserted in the carrier with the point member down, as shown in Fig. 7, or with the point member up. The opener operates in the same manner, whether the point member be up or down, but in order that the pins may be applied to the card it is necessary that all of the point members shall be in the same relative position. The means for effecting this result will now be described. The device is located in such position as to turn such pins as are improperly positioned immediately after the operation of the opener. It is shown in part in Figs. 1 and 4 and more in detail in Fig. 10. It comprises a partial gear h , suitably mounted in proximity to the carrier f' and having a projecting pin or finger h' . The gear receives a half revolution at each movement of the carrier and the pin h' strikes the point member of the safety pin which may be in front of it, if such point member is uppermost, and rotates the pin and socket with its swivel, in the bearing of the latter in the chain, through a half revolution about the axis of the swivel, thereby causing the point member to project downwardly, as shown in Fig.

10. Of course if the pin already stands with its point member downward, the pin turning device operates but without effect. The gear h is conveniently operated by a rack h^2 which is carried by a sliding bar h^3 , 70 suitably mounted and pressed to the right (in Fig. 4) by a spring h^4 placed between a finger h^5 on the bar and a fixed finger or abutment h^6 . A cam h^7 , mounted on the shaft f^8 , strikes the bar h^3 at each rotation 75 of the shaft f^8 and through the rack and gear causes a potential effective movement of the turning device. The spring h^4 restores the turning device to its normal position. 80

The cards upon which the pins are to be mounted are placed in a box k (Figs. 1, 4 and 5) having a sliding bottom k' (Figs. 5, 11-13) which carries a rack k^2 engaged by a gear segment k^3 on the end of a lever k^4 . 85 The latter is suitably fulcrumed on the frame, as at k^5 , and is connected by a link k^6 with an eccentric strap k^7 of an eccentric k^8 carried by a gear hereinafter referred to. This card feeding box is constructed and operates substantially in the same manner as card feeding devices for other machines. It will be understood, of course, that this card feeding device does not necessarily operate at each movement of the carrier, but that 90 its frequency of operation is inversely dependent upon the number of pins to be inserted in a single card. Usually this number is twelve and in such cases the card feeding device, as well as the other devices, about 100 to be described, which operate upon the pins in the card, will operate once for every twelve operations of the pin transquirer, pin opener, and pin straightener and for each twelve forward steps of the pin carrier. 105

Each card, as it is ejected from the bottom of the card box k , is delivered to a card holder m (Fig. 5) which comprises a curved plate or body m' , slotted through its upper surface, as at m^2 , in line with each pin to be 110 inserted in the card, an edge holding bar m^3 , to hold the forward edge of the card, and a temporary spring holder m^4 , consisting of a spring plate slotted to correspond with the slotted body m' , or of a series of springs 115 forming a spring comb, such slotted spring plate or spring comb being curved to conform substantially to the curvature of the body m' but not resting closely upon such body. At the time when the card is ejected from the bottom of the box the slotted body m' stands in the position represented in Fig. 11, under the stationary spring holder m^4 , so that the card, as it is ejected from the card holder k is forced into the curved space 120 between the slotted body and the spring holder until its forward edge enters the space between the forward portion of the body m' and the edge holding bar m^3 . As soon as the card is inserted in the holder the 125

130

body m' begins to move forward from the position shown in Fig. 11 toward the position shown in Fig. 12, being forced in such movement upon the point members of the pins. In such movement the card is carried out from under the spring holder m^4 , but as its forward edge is held by the edge holding bar m^3 it is forced upon the sharp points of the pins which enter the card, as clearly shown in Fig. 12, lying in the slots m^2 of the body m' . To effect the desired movement of the pin holding body m' , it is carried by a lever m^5 mounted on a shaft m^6 . The lower end of the lever m^5 stands between a rapidly rotating grooved face cam m^7 , shown in Figs. 1, 3 and 4 and in detail in Figs. 17 and 18, mounted upon a shaft m^8 , and a cam m^9 shown also in Figs. 1, 3 and 4 and in detail in Figs. 16-18, mounted loosely upon the shaft m^8 , and rotated slowly in synchronism with the operation of the card feed &c. Normally the end of the lever m^5 stands out of engagement with the cam m^7 , but after twelve revolutions of the cam m^7 the lever is thrown by the cam m^9 into engagement with the cam m^7 , so that at the proper moment, when the carrier f' is stationary, and when twelve pins are in readiness to be inserted in the card, the card holder is operated quickly, by the rapidly revolving cam m^7 , to place the card held upon the points of the pins or, in other words, to insert the pins in the card. The cam m^9 is conveniently carried by a gear m^{10} , which also, in the machine shown, carries the eccentric k^8 .

When the pins have been applied to the card, the next operation is to close the pins. This operation, also, must be effected with great rapidity when the carrier is stationary after the desired number of pins have been inserted in the card. The pin closer n (Figs. 1, 11-14) comprises a suitably notched plate n' , carried by a plunger rod n^2 sliding in a guide n^3 and having its lower end stand between a rapidly moving grooved face cam n^4 on the shaft m^8 , and a slowly revolving face cam, indicated by dotted lines at n^5 in Fig. 1, conveniently carried by the slowly revolving gear n^6 mounted loosely on the shaft m^8 . The cams n^4 and n^5 are identical in construction and operation with the cams m^7 and m^9 previously described and shown in detail in Figs. 16-18, and need not, therefore, be further illustrated in detail. The roller carried by the plunger n^2 stands normally out of engagement with the rapidly revolving cam n^4 , but after every twelfth revolution thereof is thrown into engagement therewith by the slowly revolving cam n^5 , so that when twelve pins have been inserted in a card, the closer is operated quickly to close all of the pins during the brief interval in which the pins are held stationary by the carrier f' .

It will be understood that the closer simply pushes the point members of the pin straight toward the back members and that the points are deflected by the shield or head of the pin so as to pass to one side of and into the shields or heads, with which they engage as the opener is withdrawn. The card, of course, is carried with the pin points, as clearly indicated in Fig. 13.

The final operation performed by the machine is the removal or pulling out of the pins, mounted on the card, from the carrier f' . This operation is performed when the card and the pins have moved beyond the range of the pin box and pin inserting devices, that is, in the machine shown, after twelve successive forward movements of the carrier after pins have been inserted in the card. The pin remover o (Figs. 4, 11-13 and 15) comprises a comb o' , adapted to engage the pins, as indicated in Fig. 15, carried by a link o^2 which is slotted, as at o^3 , to engage a guide pin o^4 . The link is connected to a lever o^5 (Fig. 4 and dotted lines in Fig. 5) which is mounted on the oscillating shaft m^6 previously referred to. The comb o' and link o^2 stand normally in the position indicated in Figs. 11, 12 and 13, but when a card with its twelve pins is in the proper position the comb is drawn backward and downward, by reason of the slot o^3 , so that it first engages the pins, as shown by full lines in Fig. 15, and then draws them out of the sockets f of the carrier, as indicated by dotted lines in the same figure, so that the card with its pins is then free to fall into a receptacle which may be placed to receive them. This operation of the remover takes place at the same time as the operation of inserting the pins in the next following card and takes place quickly during the brief interval for which the carrier is at rest after a forward movement.

Obviously the means for supplying power to the several devices hereinbefore described might be arranged in any convenient manner. As shown in the drawings power is applied through the pulleys p, p' on a shaft p^2 . A pinion p^3 on the shaft meshes with a large gear p^4 , on the shaft c^5 , previously referred to, which carries the cam c^4 . The shaft c^5 also carries a hand or fly wheel p^5 . A sprocket p^6 on the shaft c^5 drives the elevator, through a chain p^7 , and a sprocket p^8 on the upper shaft p^9 of the elevator. The gear q on the shaft c^5 , through an idler q' , drives a gear q^2 on a shaft q^3 . The shaft q^3 , through bevel gears q^4 , drives the shaft f^8 , hereinbefore referred to.

The gear q^5 on the shaft q^3 , through an idler q^6 , drives a gear q^7 on the shaft q^8 of the opener g . The gear q^5 also meshes with a gear q^8 on the shaft m^8 which carries the rapidly revolving cams m^7 and m^9 . The gear q on the shaft c^5 also meshes with a gear r

on a shaft r' . A gear r^2 on the shaft r' engages a gear r^3 on the shaft a^2 which carries the feeder a' .

The shaft r' , previously referred to, drives slowly through a worm s' and worm wheel s^2 , a shaft s^3 which has a gear s^4 meshing with the slowly moving gear m^{10} which carries the cam m^9 , and a gear s^5 meshing with the slowly moving gear n^6 which carries the cam n^7 , this train of gearing being so timed, in the machine shown, as to cause the cams m^9 and n^7 to rotate once for every twelve revolutions of the corresponding cams m^7 and n^4 . The gear s^5 , through intermediate idle gears s^6 and s^7 , drives a gear s^8 on a shaft s^9 to which is fixed the cam s^{10} which operates the blade c^2 for the purpose of clearing the hopper c at intervals.

A gear t on the rapidly rotating shaft m^8 20 meshes with a gear t' on the shaft e^{18} which carries the cams e^{18} .

It will be understood that the arrangement of the gearing may be varied to suit different conditions of operation or convenience in construction. The gearing shown herein is designed with reference to the proper timing of the parts necessary to perform all of the several operations described when twelve pins are to be applied to a single card. It will be understood, moreover, that as to the several devices which are operated by such gearing, one or another of such devices might be omitted and the function thereof performed by hand and that any of such devices is capable of performing its intended function either by itself or in combination with some or all of the other devices described.

Changes may be made within the scope of 40 the invention as set forth in the appended claims.

I claim as my invention:

1. In a machine for handling safety pins, the combination of a stationary hopper in 45 which the pins to be handled may be placed, a second and stationary hopper having inclined sides and a slotted, inclined bottom whereby the pins are uniformly positioned with respect to their transverse axes, and positive means to transfer the pins to be handled from the first named hopper to the second named hopper.

2. In a machine for handling safety pins, the combination of a hopper in which the 5 pins to be handled may be placed, a conveyer, a rotating feed roll mounted between the hopper and the conveyer and having projections to transfer the pins to be handled from the hopper to the conveyer, and a second hopper to which the pins are delivered by the conveyer, said second hopper having inclined sides and an inclined, slotted bottom.

3. In a machine for handling safety pins, 35 the combination of a hopper in which the

pins to be handled may be placed, a conveyer, a rotating feed roll mounted between the hopper and the conveyer and having projections to transfer the pins to be handled from the hopper to the conveyer, a 70 second hopper to which the pins are delivered by the conveyer, said second hopper having inclined sides and an inclined, slotted bottom, and means to agitate the pins to cause them to drop partly through the 75 slotted bottom of the second named hopper.

4. In a machine for handling safety pins, the combination of an inclined guide along 80 which the pins to be handled are moved by gravity, a traveling carrier adapted to receive the pins, and independent means to transfer the pins one by one from the guide to the carrier.

5. In a machine for handling safety pins, the combination of an inclined guide along 85 which the pins to be handled are moved by gravity, yielding stops at the end of the guide to prevent the accidental release of the pins, a transversely traveling carrier adapted to receive the pins and means to 90 transfer the pins one by one from the guide to the carrier.

6. In a machine for handling safety pins, the combination of means to supply the pins in a succession, a transversely traveling carrier adapted to receive a plurality of pins and means independent of the supply means 95 and carrier to transfer the pins one by one from the supply to the carrier.

7. In a machine for handling safety pins, 100 the combination of an inclined, slotted guide adapted to permit the movement of safety pins by gravity with their ends resting upon the guide members and their bodies depending through the slot, a traveling carrier having sockets to receive the pins, and means to transfer the safety pins one by one from the guide to the carrier.

8. In a machine for handling safety pins, 110 the combination of a slotted guide adapted to permit safety pins to move thereon by gravity with one end supported upon the guide members and the body depending through the slot, spring stops at the end of the guide to engage the ends of each pin 115 and prevent its accidental disengagement from the guide, a traveling carrier having sockets to receive the pins and means to transfer the pins one by one from the guide to the carrier.

9. In a machine for handling safety pins, 120 means to supply the pins to be handled, a uni-directional traveling carrier adapted to receive the pins, nippers adapted to grasp a pin as presented by the supply means, and means to actuate said nippers to grasp and release the pin and to move the same bodily to transfer the pin from the supply means to the carrier.

10. In a machine for handling safety pins, 125

- the combination of a slotted guide for safety pins adapted to permit the coil end of each pin to rest upon the guide with its body depending through the slot, a carrier having 5
5 sockets to receive the pins, nippers adapted to grasp the coil end of each pin as it is presented by the guide, and means to actuate said nippers to grasp and release the pin, to transfer the pin from the guide to the carrier and to turn the pin in its movement 10 and present its end to the socket in line therewith.
11. In a machine for handling safety pins, the combination of a uni-directional traveling carrier adapted to receive the pins in succession, positive means to apply the pins to the carrier, and an opener to open such pins as may be closed. 15
12. In a machine for handling safety pins, the combination of means to supply the pins, a traveling carrier to receive the pins, positive means to bodily transfer the pins in succession from the supply to the carrier, and an opener to open such pins as may be closed. 20
13. In a machine for handling safety pins, the combination of a traveling carrier adapted to receive the pins, positive means to apply the pins in succession to the carrier, a finger to press upon the point member of the pin while held in the carrier and release it from the head of the pin, and means to actuate said finger. 25
14. In a machine for handling safety pins, the combination of a traveling carrier adapted to receive the pins in succession, opposing fingers adapted to press upon the point member and the back member of the pin and release the point member from the head of the pin while the pin is held by the carrier, and means to actuate said fingers. 30
15. In a machine for handling safety pins, the combination of an endless chain carrier adapted to receive the pins, opposing levers 45 mounted in proximity to the carrier and provided with fingers to press upon the point member and back member of the pin and disengage the point member from the head of the pin, and means to actuate said levers.
16. In a machine for handling safety pins and the like, a carrier consisting of an endless chain provided with sockets to positively grip the ends of the safety pins or the like to retain the same. 50
17. In a machine for handling safety pins and the like, a carrier having swiveled sockets to receive the pins and permit the rotation thereof. 55
18. In a machine for handling safety pins and the like, a carrier consisting of an endless chain provided with swiveled sockets to receive the pins and permit the rotation thereof. 60
19. In a machine for handling safety pins and the like, the combination of a carrier 65 adapted to receive the pins and means to turn the pins while held by the carrier so that their point members may occupy the same relative positions.
20. In a machine for handling safety pins 70 and the like, the combination of a carrier having swiveled sockets to receive the ends of the safety pins or the like, and means to rotate the pins while held in the swiveled sockets so that their point members may 75 occupy the same relative positions.
21. In a machine for handling safety pins and the like, the combination of a carrier adapted to receive the pins and permit them to be turned therein, and a turner therefor 80 comprising a finger adapted to coöperate with the open point member of the pin, and means to support and rotate said finger in contact with the point member of the pin to turn the pin. 85
22. In a machine for handling safety pins, the combination of a carrier adapted to receive the pins and permit the same to be turned therein, a segmental gear mounted upon an axis parallel with the carrier and 90 having a finger to coöperate with the open point member of a pin while held in the carrier, and means to rotate said gear with its finger to turn the pin. 95
23. In a machine for handling safety pins, the combination of a carrier having swiveled 100 sockets to receive the pins, means to apply the pins to the sockets and a turner to turn a pin held in the socket to a uniform position.
24. In a machine of the character described, the combination of a traveling carrier adapted to receive and support the articles to be handled, means for imparting a step by step movement to the carrier, and 105 means to bodily transfer the articles one by one to the carrier in its successive positions of rest. 100
25. In a machine of the character described, the combination of a traveling carrier having sockets to receive the articles, means to impart a step by step movement to the carrier, means to supply the articles, and means to bodily transfer the articles one by one from the supply means to the sockets of 115 the carrier. 110
26. In a machine for handling safety pins, the combination of a carrier adapted to receive the pins, an opener to open such pins as may be closed while held by the carrier, 120 and a turning device to turn the pins to the same relative positions while held by the carrier. 120
27. In a machine for handling safety pins, the combination of a carrier having swiveled 125 sockets to receive the pins, an opener to open such pins as may be closed while held by the carrier, and a turning device to turn the pins to the same relative positions while held by the carrier. 120

28. In a machine for carding safety pins, the combination of a carrier to receive the pins, an opener to open such pins as may be closed, a turning device to turn the pins to the same relative positions, a card holder and means to cause the point members of the pins to be inserted in the card.

29. In a machine for carding safety pins, the combination of a movable body, curved and slotted, an edge holding bar movable with the body, and a stationary spring comb curved to conform to the body.

30. In a machine for carding safety pins, the combination of a card holder, means to feed the card to the holder, means to support the pins with their point members open, and means operative upon the introduction of a predetermined number of pins to the support to move the holder with the card to cause the point members of the pins to be inserted in the card.

31. In a machine for carding safety pins, the combination of a movable holder, curved and slotted, a stationary spring comb, curved to conform to the body, means to feed the cards to the holder, means to support the pins with their point members open, and means to move the holder from its position adjacent to the spring comb to

cause the point members of the pins to be so inserted in the card.

32. In a machine for carding safety pins, the combination of means to support the pins with their point members open, a card holder, means to move the same to cause the point members of the pins to be inserted in the card, and a pin and card remover and means to actuate the same to withdraw the card and pins from the pin holding means.

33. In a machine for carding safety pins, the combination of a carrier adapted to receive the pins and support the same with their point members open, means to impart a step by step movement to the carrier, means to apply the pins one by one to the carrier in its successive positions of rest, a card holder and means to actuate the same after a succession of operations of the devices for applying pins to the carrier to cause the point members of the pins held by the carrier to be inserted in the card on the holder.

This specification signed and witnessed this sixth day of Aug., A. D. 1908.

HERBERT B. CHURCH.
